25 Claims. (Cl. 178—7.6)

This invention relates to television or like transmitters of the type wherein either an image of the picture to be transmitted is formed on a Nipkow disk, by means of optical projection apparatus, or an image of holes in a Nipkow disk is formed on the picture to be transmitted, the image of the picture (or the picture itself) being scanned by the holes (or their image), respectively, as the case may be.

10 It is well known that, when the signals from such transmitters are received by a cathode ray tube, a characteristic form of distortion, known as keystone distortion, arises in the following way. During a single picture frame period, during which a single picture is reproduced, the spot, controlled by equally spaced line-frequency synchronising signals, traverses the cathode-ray screen M times in a series of M parallel lines, all equidistant, of equal length, traversed in equal times, forming together a substantially rectangular area. Each of these lines corresponds with the traverse of a single hole in the Nipkow disk across the image. If therefore, the picture on the screen is to reproduce accurately the image on the disk, the holes must traverse the image in a series of straight lines all equidistant, of equal length, and traversed in equal times. The paths of the holes can be so little curved that they can be taken as straight. Equidistance of these paths can be secured (it will appear later that it is not always desirable); but if, as is implied by the term Nipkow disk, the holes on the disk are arranged on a spiral and not on a circle, the combination of equal lengths with traverse in equal times cannot be attained. For the holes nearer the centre will travel slower than those more distant.

40 A precisely similar kind of distortion arises with other types of receiving apparatus (such as those using a mirror drum) which use constant velocity scanning for the reconstruction of the picture.

If the image on the disk is still and rectangular, and if the scanning is plain (i. e. not interlaced), 45 the result is a true keystone distortion. (For brevity we shall suppose that the top line of the picture on the cathode ray screen corresponds with the outermost hole on the disk.) If the speeds of the disk and of the scanning spot are 50 adjusted, so that the time of traverse of a spot across the screen is equal to the time of traverse of the innermost hole of the disk across the image, then the bottom line of the picture will occupy exactly the full width of the rectangular 55 area on the screen. But then the time of traverse

of the outermost hole will be less than the time of traverse of the spot, and the top line of the picture will occupy part only of that width. If the rectangular image on the disc is framed by a black border, the image on the screen will taper from the bottom upwards.

One way of abolishing the taper is to make the image on the disk, not rectangular, but keystone-shaped in the reverse sense, that is to say, increasing in width from the centre outwards. 10 If the original picture were rectangular, it might be projected on the disk unaltered in shape and the image masked appropriately. This simple procedure, although (as will appear later) it has some applications, would not be a real cure; for though the outline of the picture on the screen would be rectangular, the lower lines would be reproduced on a larger scale than the upper. An alternative method, proposed in the specification of British Letters Patent No. 464,831 and producing a real cure, is to change the rectangular 15 picture into a keystone-shaped image in the course of projection, for example by reflections on surfaces inclined to the optical axis of the projector. But such reflections are apt to introduce aberrations which militate against perfect 20 definition.

25 A far more serious distortion arises from the same cause when the image is that of a moving film and the scanning is interlaced. It is unnecessary here to enter into the full theory of the 30 interlaced scanning of moving films; it will be sufficient to point out the relevant characteristics of one well-known form of it, which is described and claimed in the specification of British Letters Patent No. 465,184. A description is also to be 35 found in the specification of British Letters Patent No. 466,051.

40 In this form the centre line of the image of the film moves outward along a line through the centre of the disk at the same speed as the 40 scanning hole moves inward, the radial distance between the outermost and innermost holes being equal to the length of a single picture in the image. The number of scanning holes is odd, 45 say $2N+1$; the holes are arranged on P turns of a spiral; P may be any integer from 1 upwards, but is usually 2 or 4; if P is greater than 1 (as is prescribed in the said specification No. 465,184) some device (for example an interceptor disk) 50 is provided to secure that at any given moment the holes in one turn only are effective. (It is possible in principle that P should be non-integral, but it is unnecessary to discuss this possibility in detail, since the value of P is not 55

directly relevant to the invention.) Let these holes be numbered by consecutive integers starting with the outermost. Then (subject to a later consideration) $2N+1$ lines are scanned on each picture and have to be reproduced in their proper order on the cathode ray screen; let them be numbered by consecutive integers starting from the leading edge of the moving image on the disk. The consequence important for our purpose is that the odd numbered lines are all scanned by holes nearer the centre of the disk, while the even numbered lines lying between them are all scanned by holes further from the centre. More specifically, the $(2n+1)$ th line (n=0 to N) is scanned by the $(N+n+1)$ th hole, while the $2n$ th line (n=1 to N) is scanned by the nth hole.

The result is that the odd and even number lines form on the screen a picture subject to simple keystone distortion, but the even number lines are all shorter than the odd number lines between which they lie.

It is an object of the present invention to provide an improved method and means for eliminating the keystone distortion arising from the varying speed of the scanning holes of a Nipkow disk.

A further object of the present invention is to provide means for eliminating the distortion caused by the varying speed of the scanning holes of a Nipkow disk in a television system transmitting an image of a moving film using interlaced scanning.

Other objects of this invention will appear during the course of the following description and drawings in which:

Figure 1 and 2 show diagrammatically, and for the purpose of explanation, the nature of the distortion produced by an interlaced scanning of a moving film, Figures 3, 4 and 5 illustrate diagrammatically the removal of this distortion by means of the present invention.

Figure 6 shows diagrammatically a side elevation of an optical projector utilizing the invention.

Figure 7 shows a side elevation of a rotatable disk for use with the projector shown in Figure 6.

Figure 8 shows a cross-sectional view of the disk shown in Figure 7.

Figure 9 shows for the purpose of explanation one form of a mask.

Figure 10 shows an improved mask.

Figure 11 shows a portion of a cinematograph film.

Figure 12 shows an alternative form of mask.

Figure 13 shows an explanatory diagram illustrating the derivation of the mask shown in Figure 12, and

Figure 14 is a cross-section on a reduced scale of the mask shown in Figure 12.

Figures 1 and 2 are explanatory diagrams showing how distortion occurs in the above described system of transmitting an image of a moving film when using interlaced scanning. Here, and in other figures to be described later, N is taken as 6, and the difference in the length of the lines is greatly exaggerated; it would be impossible to show the true result clearly in a drawing of practicable size. In Figure 1, there is shown the image on the screen at a particular instant, and the positions on it of the $2N+1$ lines, numbered on the left, that have to be reproduced on the screen. In Figure 2 there is shown how these lines appear on the screen not, of course, simultaneously, but in succession. The numbers on

the right are those of the holes by which the lines are scanned. The order in time of appearance is not that of either set of numbers; the order in which the lines of Figure 1 appear on the screen is 1, 3, 5, 7, 9, 11, 13, 2, 4, 6, 8, 10, 12. There is no necessary relation between the length of the lines in Figure 2 and the length of the lines in Figure 1; relative lengths within Figure 1 or within Figure 2 alone matter.

It will be seen that the odd and even lines each form on the screen a picture subject to simple keystone distortion; but the even lines are all shorter than the odd lines between which they lie. Let d be the distance of the outermost hole from the centre of the disk, δ the radial distance between consecutive holes, $\lambda=1-N\delta/d$. $N\delta/d$ will be much less than 1, probably about 0.025. Then, with sufficient accuracy, the ratio of the length of the top line in Figure 2 to the length of the bottom line will be λ , and so will be the ratio of an even-numbered line to the pair of odd-numbered lines between which it lies. (For the purpose of the drawing $N\delta/d$ has been taken as $\frac{1}{2}$.) If the image had been still and the scanning interlaced, the ratio of the length of the top to that of the bottom line would have been

$$1 - \frac{2N\delta}{d}$$

Accordingly the interlaced scanning halves the general keystone distortion, but it introduces a difference between successive lines that is far more objectionable.

This distortion, which is due, as previously mentioned, to the varying speed of the holes in the scanning disk, cannot be abolished by any practicable masking but is obviated by the present invention which broadly consists in providing means in a television or like transmitter of the type specified, whereby the magnification of the optical projection means is varied in time so that the magnification is less when the image is being scanned by holes nearer the centre of the disk than when it is being scanned by holes further from the centre of the disk. "Magnification" means, as usual, the ratio of a linear dimension of the object; of course this ratio may be, and usually will be, less than 1. The use of the term "magnification" implies that the ratio is substantially constant over the image, which is therefore undistorted.

In regard to the principle of the present invention, the following points should be understood. Let the holes in the disk be numbered by consecutive integers r from the outermost hole inwards so that the distance from the centre decreases as r increases. Then, in order that the principle described above should be used, and in order that the apparatus should fall within the invention, it is necessary that when some hole r is scanning, the magnification is greater than when any hole $(r+s)$ is scanning, and not greater than when any hole $(r-s)$ is scanning, s being positive. It is not necessary that the magnification should be greater when every hole r is scanning than when any hole $(r+s)$ is scanning. When interlaced scanning is employed, some further condition must usually be imposed, dependent upon the nature of the interlacing, and the extent to which keystone distortion is to be avoided. Thus, for the interlaced system discussed above, a suitable further condition to impose is that the magnification is the same for all values of r from 1 to N, and the same for all

values of r from $N+1$ to $2N+1$, but is greater for the former values.

The application of the invention to an interlaced scanning system of the kind described above 5 will now be described with reference to Figures 3, 4 and 5 of the accompanying drawings.

In accordance with our invention, a television or like transmitter of the type specified which is provided with a Nipkow disk arranged to produce interlaced scanning on a continuously moving film is provided with an optical projection system whose magnification undergoes a temporal variation as the Nipkow disk rotates. The speed with which the film moves may be either constant 10 or variable, provided that the film is not brought to rest for an appreciable proportion of the period during which each picture is being scanned. Transmitters in accordance with the present invention are accordingly distinguished from transmitters using previously known methods of correcting for the effects of keystone distortion in that while in the previously known methods the magnification of the image-producing means remained invariable in time (although, in some 15 cases, being different at different points of the image), in the present arrangement the magnification of the image-producing means is varied from time to time during the rotation of the Nipkow disk—such variation being effected either 20 continuously or at suitable instants at which the Nipkow disk is in the appropriate position or positions.

Figures 3 and 4 show, respectively, the image on the screen at two different instants; Figure 3 refers to an instant at which the image is being scanned by one of the holes $N+1$ to $2N+1$; Figure 4 refers to an instant at which it is being scanned by one of the holes 1 to N . Between these two instants the magnification of the optical projection apparatus has been changed, so that the image Figure 3, is smaller than the image Figure 4 in the ratio λ . The lines which will be scanned when the image has the size of Figure 3 (or Figure 4) are marked on the left of said figures. The picture on the screen will appear as shown in Figure 5. Since the even numbered lines in Figure 4 are longer in the ratio $1/\lambda$ than the odd numbered lines in Figure 3, the length of the even-numbered lines in Figure 5 will be greater 25 in that ratio, relative to the length of the odd-numbered lines, than they were in Figure 2. There will be no longer a difference between alternate lines; but the whole picture will be subject to simple keystone distortion in the ratio λ . 30 Instead of changing the magnification of the optical system discontinuously from one fixed value to another as just described, the magnification could be changed continuously between the two extreme values. With this arrangement, in 35 an interlaced scanning system, the resulting picture would be produced free from both the distortion due to the difference in length of alternate lines and the remaining simple keystone distortion, while in the case of a non-interlacing scanning system, the resulting simple keystone distortion could in the same way, be abolished.

The required change in magnification, which must be effected without any substantial change in the position of the image plane, is obtained 40 by means of a known kind of compound lens in which an effective displacement of one component thereof produces a change in magnification without any substantial change in the position of the image plane corresponding with a given object plane.

The design of lenses having the properties just stated forms no part of the invention. It is sufficient therefore to record that such lenses can be obtained from Messrs. Taylor, Taylor & Hobson of Leicester. Of course, it is not implied that 5 they cannot be obtained elsewhere.

Since the changes of magnification have to be made with extreme rapidity (e. g. 50 times a second), actual displacements of the components would be inconvenient; but displacement can be 10 simulated by change of the refractive index of the medium between the components. The refractive index might be changed by using as the medium, one of the known kind, the index of which is varied by an applied electric field, but 15 a simpler method is to introduce a glass plate between the components. Since glass is of higher refractive index than air, the introduction of a glass plate on one side of the said component, accompanied by removal of a glass plate from 20 the other side of the said component, can be made equivalent, to a first approximation, to displacing the said component towards said first plate.

It will be understood that transparent materials other than glass may be used if desired, it being only necessary, in principle, that the material used should have a refractive index different from the air or other medium in which the lens components are immersed; and where the term 25 "glass" is used in the claims appended hereto, that term is to be understood to comprehend other suitable transparent materials having a refractive index different from that of the medium in which the lens system is immersed. 30

One way of introducing and removing the glass plates is to mount two semi-circular plates on the same shaft, so that (1) the plane of one lies on one side of the said component, and the plane of the other on the other side, both these planes 40 being perpendicular to the axis of the shaft, (2) the bounding diameters of both plates are coplanar with the said axis which bisects both of them, (3) the two plates are on opposite sides of the plane mentioned under (2). When the shaft 45 is rotated one or other will always intersect the axis of the lens, but never both. The speed of rotation of the disc must be

speed of rotation of the scanning disk

P

50

so that the position of the plates is restored at the instant when any given hole scans again. Since the introduction of one plate and the removal of the other has to be completed during the 55 short period (usually occupied by the black margin of the picture, between the two interlaced scans, the circumference of the plates must be much greater than the diameter of the light beam where it passes through the plates; but, as the 60 example given below will show, the size of the plates required is not prohibitive.

It is obvious that more complicated arrangements might be used. The plates might be segments of a circle including any angle $180^\circ/p$, 65 where p is integral. Then p of them have to lie in each plane on one side or the other of the said component, the angular distance between these adjacent edges being always $180^\circ/p$; and the spaces in one plane have to be opposite the plates in the other plane, that is to say, any line 70 parallel to the axis of rotation and intersecting the cross section of the beam of light has to intersect a plate in one plane and pass between two 75

plates in the other. The speed of rotation must then be

speed of rotation of the scanning disk

20^P

Again the essential feature of "introducing" (or "removing") a plate is the increase (or decrease) of the thickness of glass in the path of the beam; it is not essential that this thickness should be reduced to zero. Accordingly, a circular plate of any constant thickness might be associated with the plate(s) aforesaid which lie in one plane; in other words, the plate(s) might be thicker portions of a continuous circular disk.

15 Lastly, it will usually be necessary for mechanical reasons to support the glass plates at their adjacent edges by opaque metal, so that there is a portion of the plane in which they lie which is neither glass plate nor transparent space between glass plates. These opaque portions will be arranged to cross the beam of light during the said short period occupied by the black margin. Accordingly the segments constituted by the glass plates will not be exactly of angle $180^\circ/p$, but will be substantially $180^\circ/p$, so that outside this short period, the effect is the same as if the angle were $180^\circ/p$.

Apparatus adapted to produce a change in magnification, in the manner described above, will now be described, by way of example, with reference to Figures 6, 7 and 8 of the accompanying drawings.

Figure 6 shows the general arrangement of the apparatus. 21 is a casing supporting the components of the lens. The outermost components 22 and 23 are fixed in the sides of the casing, the central component 24 is supported on a pedestal 25 within it. Above all these components the shaft 26 passes through bearings 27, 28 in the sides of the casing; it is driven by a synchronous motor. The glass plates are supported on this shaft so as to lie in the planes 29, 30. The plane of the film is shown at 31, that of the image on the disk at 32. The distances marked on the figure have the following values:

50 $a = 102$ mm.
 $b = 81$ mm.
 $c = 41$ mm.
 $d = 29$ mm.
 $e = 88$ mm.
 $f = 66$ mm.
 $g = 120$ mm.

55 f is the maximum width of the beam of light. The components of the lens are such that the mean magnification is $1/1.5$; it could be varied by 2.5% by displacing the central component 24 by 2.39 mm. along the optical axis.

Figure 7 shows in plan, and Figure 8 shows in section, the construction of the disks which rotate with the shaft 26 in the planes 29, 30. Both disks are similar. p aforesaid is 1, so that the disks are displaced relatively to each other by rotation through 180° about the shaft, as well as by translation from 29 to 30 (or vice versa) along it.

Each disk consists of a steel frame 33 which is milled out of a solid plate. 34 is a central hole to take the shaft 26; 35 a hole which is the space in the aforesaid description; 36 is a flanged hole into which the glass plate 37 fits and is held by tongues 38. It will be observed that the disk is asymmetrical about the diameter which separates the glass from the space, in order that it may be approximately balanced when the glass

is inserted. Adjustable means of the usual kind for final balancing (not shown) are provided.

The distances shown on Figure 7 have the following values:

$g = 120$ mm.
 $h = 2.649$ ins.
 $j = 2.993$ ins.
 $k = 6.722$ ins.
 $l = 6.500$ ins.
 $m = 0.250$ ins.
 $n = 3.031$ ins.
 $r = 6.142$ ins.

The glass is 6.98 mm. thick; its refractive index for light of wave-length 7500 Å. is 1.5222. It is to be observed that since the refractive index varies with the wave-length, it is not usually possible to arrange that the magnification is the same for all wave-lengths, so that the system is achromatic. The wave-length for which adjustment is made is that at which the photoelectric cells to be used with the apparatus are most sensitive; their cathodes are, as usual, of the caesium-oxygen-silver type. A red filter, transmitting preferentially the light to which the cell is most sensitive, may be inserted in the path of the light to eliminate light of wave-length very different from that for which the adjustment is made.

However there is a complication that has been 30
ignored. In order to substitute the picture of
Figure 5 for the picture of Figure 2, it is neces-
sary to vary only the circumferential magnifica-
tion, that is to say, the magnification parallel 35
to the tangent of the circle traversed by a hole
at the point where it is midway between the two
sides of the image at which the hole enters and
leaves the image. The methods just proposed
for varying this magnification would usually vary 40
in the same ratio the radial magnification, that
is to say, the magnification parallel to the radius
of the said circle at the said point. But if the
radial magnification is reduced when the picture
is being scanned by the holes nearer the centre, 45
and if the pitch of the spiral on which the holes
are arranged is the same both near the centre
and remote from it, the lines produced in the
received picture by the holes nearer the centre
will be further apart than those produced by 50
the holes further from the centre. Accordingly
the lines produced by one set of holes will not
fit uniformly between the lines produced by the
other set of holes, as they must if correct inter-
laced scanning is to be obtained.

This change in the position of the lines perpendicular to their length is not shown in Figure 5. Subsidiary means must be provided for compensating the variation of the radial magnification, but not the variation of the circumferential magnification, so that Figure 5 represents the result accurately. 55 60

The simplest and preferred subsidiary means is a variation of the pitch of the spiral on which the scanning holes lie. Thus, if the magnification is reduced in the ratio λ when the change takes place between the scanning of the even lines by the outer holes and the scanning of the odd lines by the inner holes, then the pitch of the spiral (and therefore the radial distance between successive holes) must be reduced at the same time in the ratio λ . This reduction can, of course, be achieved by spacing the holes suitably when the disk is made. 65 70

Alternatively the subsidiary means might vary the speed with which the image travels over the 75

disk. The condition that has to be fulfilled, in order that the variation of radial magnification shall be compensated, is that the time occupied by the image in traversing the radial distance 5 between two successive holes should remain unchanged when the magnification is changed.

Reduction of magnification involves a reduction in the same ratio, of the speed with which the image travels radially over the disk. Reduction of the radial spacing between the holes, as aforesaid, reduces the distance to be travelled in the same ratio, and therefore keeps constant the time in which the distance is travelled. But it could also be kept constant by increasing again 10 the speed with which the image travels, so as to abolish the reduction of speed associated with reduced magnification, the radial spacing of the holes remaining constant. This compensating increase of speed can be effected by increasing 15 the speed with which the film, the image of which is projected, travels through the projecting apparatus past the gate, for example by suitable cams and other devices, obvious to those skilled in the art, in the driving mechanism. 20 But, owing to the rapid changes of speed necessary, this method is not likely to be suitable except in special circumstances.

Lastly, subsidiary optical means might be employed which actually prevent change of the radial magnification. Thus, if a suitable cylindrical lens, with its axis parallel to the said tangent, were introduced into the path of the projecting beam at a suitable point at the moment when the circumferential and radial magnifications of the main optical system are changed, it could (in principle at least) produce a change in the radial magnification opposing the change in the radial magnification of the main system. If the magnification of the main 35 system is changed (as suggested above) by the introduction of a glass plate between the components of the main projecting lens, this cylindrical lens might possibly be combined with the plate; the part of the plate which intervenes in 40 the optical path could be made a cylindrical lens of suitable curvature with a circular axis coinciding with the circle along which the said part of the plate travels.

But even now two forms of distortion remain. 50 One is the simple keystone distortion shown in Figure 5. This can usually be removed adequately by a mask as indicated above. If the mask were immediately before the surface of the disk, it could be of the simple form shown in 55 Figure 9 of the accompanying drawings. Here 39 is the disk, 40 the mask, exposing the trapezoidal area 41 of the disk. 42 is the rectangular image thrown on the mask. The sides 43, 44 are radii of the disk; the ends 45 and 46 are so 60 far apart that all the scanning holes pass between them. Now every hole takes the same time to cross the area 41, so that there is no inclination of the vertical edges of the reproduced picture; at the same time, the advantage 65 is obtained of a border of constant blackness. But the part of the picture that falls on the mask is sacrificed; moreover, as said before the lower lines are reproduced on a larger scale than the upper. However these defects will often be 70 negligible.

Generally it is more convenient to place the mask, not at the disk, but at the gate over which the film passes, and indeed to make the mask the gate. But now it must be remembered that, 75 while they are being scanned, the two halves of

the picture will be magnified differently; the masks must be adjusted so that the two halves, each subjected to the appropriate magnification, combine to form on the disk an image such as is shown in Figure 9 aforesaid. The mask at the 5 gate will thus take the form shown in Figure 10 of the accompanying drawings. It consists of two superimposed trapeziums 47, 48, 49, 50 and 51, 52, 53, 54 which are such that the first (or second), if increased (or decreased) circumferentially in the ratio $1/\lambda$ (or λ), assumes the form 47', 48', 52, 51, (or 50, 49, 53', 54') so that the effective aperture of the mask, 47', 48', 53, 54 (or 47, 48, 53', 54'), is similar to the outline of the area 41 in Figure 9. 15

An alternative form of gate and mask will now be described with reference to Figures 11-14.

The pictures proper on a moving film each of length $H-x$, are separated by a strip of length x , usually black and hereinafter called black, 20 bearing no picture; this arrangement is shown in Figure 11 of the accompanying drawings. The pictures that have been considered above, scanned in $2N+1$ lines are necessarily coterminous; they therefore include not only the picture proper, but a strip of black, $x/2$ in length, 25 on either side of it. This strip should appear on the screen as dead black.

An examination of the formula given above, or of the numbers on the right of b in Figure 2, 30 shows that the holes which scan these black strips are those numbered 1 to q , $(N+1-q)$ to $(N+1+q)$, and $(2N+1-q)$ to $(2N+1)$, where q is an integer near (i. e. differing by not as much as 2 from) $(2N+1) x/4H$. They are thus holes 35 either at the two ends of the spiral or at its middle. The only function of these holes is then to produce a dead black border for the picture in the screen; they will do this most efficiently if they are completely blocked; for then 40 black will be produced whatever the density of the black on the film. They may actually be blocked on the disk; but, at least so far as the middle holes are concerned, it is preferable to block them effectively by obstructing matter in 45 the gate, the image of which is projected on the disk. The gate may therefore be shaped as shown in Figure 12 of the accompanying drawings. It is derived from the gate shown in Figure 13 of the accompanying drawings, supposed 50 of height H , by reducing that height by a strip $x/4$ at either end and by placing a bar of height $x/2$ across the middle. This bar fulfills another very important function, namely, that of keeping 55 the film flat on the gate and preventing irregularities in its motion, which are particularly serious when the scanning is interlaced; indeed this will often be its main rather than a subsidiary purpose. Of course, the bar could be introduced equally if the gate were rectangular, 60 and there were no masking to reduce keystone distortion. Its use is possible whenever, in virtue of interlaced scanning, there are holes in the disk, intermediate between the ends of the spiral, which never scan any part of the picture 65 except the black margins.

It is usual to bevel the edges of a gate so as to avoid a penumbra on the film. It is also desirable to bevel the edges of the bar; the bevelling needs careful design because light has to reach 70 the film near the edge from both sides (and not only one side) of the edge; but with a suitable projecting system a penumbra can always be avoided.

A suitable form of bevelling is indicated in Fig- 75

ure 14, which shows diagrammatically the cross-section through the gate shown in Figure 12. The film 55 travels over the face of the gate member 56 which carries the bar 57; and in 5 order to assist in keeping the film 55 in place on the surface of the gate member 56, a pressure plate 56' is provided, this plate 56' carrying a bar 57'. As will be seen in the drawing, the edges 58, 59, 58', 59', of the gate apertures, and 10 the edges 60, 61, 60', 61', of the bars 57 and 57' are likewise bevelled, so that they do not interfere with the light passing through the gate apertures.

An alternative method of removing the key- 15 stone distortion shown in Figure 5 would be to change the magnification of the optical apparatus continuously between the two extremes and not discontinuously. Thus if, while the last (N+1) holes were scanning, the magnification 20 decreased linearly with time from m (say) to λm ; if it changed discontinuously to m/λ during the change from the $(2N+1)$ th to the 1st hole; and if, while the first N holes were scanning, it decreased linearly with time from m/λ to m ; 25 then, as an examination of Figure 2 will show, a picture would be produced on the screen free from both keystone distortion and from a difference between alternative lines. Such changes might be produced by tapering suitably the thick- 30 ness of the glass plates, mentioned above in describing the preferred method of varying the magnification. But, unless the diameter of the lens is very small compared with the length of the circle on the plates passing through the 35 lens, the tapering plate will act as a prism displacing the image appreciably.

But yet another form of distortion remains, which affects not the shape of the reproduced picture, but the distribution of illumination in 40 it; the ratio of the mean brightness of the part of the reproduced picture scanned by the holes nearer the centre to the mean brightness of the part scanned by the holes further from the centre will not be the same as the ratio of brightnesses 45 of the corresponding parts in the original picture. For the change of magnification will produce a change of brightness in the resulting image, the brightness usually increasing as the magnification decreases. All these differences of bright- 50 ness in the image will produce corresponding differences of lightness in the picture on the screen. Accordingly in Figure 5 the odd-numbered lines, since they result from the scanning of an image of small magnification, will usually 55 be brighter than the even-numbered lines. Means are therefore preferably introduced for correcting this brightness distortion.

One method always available for the correction of brightness distortion is that mentioned in the 60 specification of British Letters Patent No. 466,780, namely, the introduction into the projecting beam, where an image is formed, of material of which the absorption for light varies over the image, so that it is great at those parts of the 65 image which, in the absence of the material, would correspond with abnormally bright parts of the reproduced image and is small at those corresponding with abnormally dull parts. This method usually requires the formation of an 70 image in some plane other than that of the disk. This plane, at which the material is placed, preferably lies between the source of light and the disk, but might lie between the disk and the photoelectric cell or other receiver.

75 In a second method, the absorption in the

path of the projection beam is varied, not in space, but in time. Thus when that part of the image is being scanned which is apt to be too bright in the reproduced picture, absorbing matter is introduced into the beam, when the parts 5 apt to be too dull are being scanned, the absorbing matter is removed. This method is most suitable in connection with the aforesaid preferred method of varying the magnification, so long as at least one glass plate is present between 10 the components of the projecting lens when the brightness is relatively great. For this plate can be caused to absorb the light sufficiently to reduce the intensity of the projecting beam in the desired ratio. The term "absorb" is to be interpreted widely; it includes loss of light in the beam due to reflection, as well as that due to true absorption.

In the third method, possible in principle, but 20 likely to be difficult to apply in practice, the intensity of the beam is varied in time, not by introducing absorbing matter, but by varying the output of the source. If the disk is driven synchronously with the alternations of the main supply, the source of light may be a lamp fed by 25 the same supply and the flicker, characteristic to a greater or less extent of all lamps run on A. C., may be used to compensate the brightness distortion.

In a fourth, and generally preferable method, 30 the brightness distortion is compensated by a variation of the area of the holes in the disk. These holes which, if the area of all holes were the same, would produce too low an illumination in the reproduced picture may be made slightly 35 larger than the others. The advantage of this method of compensation is that it can be used however complicated the brightness distortion may be. For differences in brightness will always be associated with different holes and can 40 therefore be compensated by variations in the holes. Further, the method lends itself most readily to an adjustment of the compensation by trial, rather than by calculation, which will 45 almost always be necessary.

In yet a fifth method, the brightness distortion itself is left unaltered and the correction is applied to the electrical signals produced by the light when they act on the photoelectric cell or other receiver. Thus the primary current through the photoelectric cell will always be amplified, for example, in amplifying valves or in secondary emission electron multipliers; it will be obvious to those skilled in the art that the gain of these stages may be varied so as to compensate 50 for brightness distortion, and so that the signals finally emitted from the transmitters are free from this distortion. Further, if (as is usual) the television transmitting apparatus generates 55 electrical synchronising signals determined by the passage of the individual holes across the image, it will be obvious how these signals may be used to vary the gain in the appropriate manner.

Of course any of these methods may be used 60 in conjunction with any of the others.

We claim:

1. A television or like transmitter of the type specified including a Nipkow disk having scanning apertures suitably disposed to produce an interlaced scan on a continuously moving film, 70 an optical projection system associated with said disk and means for varying temporally the magnification of said optical projection system with reference to the radial distance, from the centre of said disk, of the hole by which scanning is 75

being performed, whereby the magnification of said optical projection system is reduced as the radial distance of said hole decreases.

2. A television or like transmitter of the type specified including a Nipkow disk having scanning apertures suitably disposed to produce an interlaced scan on a continuously moving film, an optical projection system associated with said disk, said optical projection system comprising 5 10 a compound lens of the kind in which an effective displacement of one component changes the magnification of said compound lens, but does not change substantially the position of the image plane corresponding with a given object 15 plane, and means for producing from time to time an effective displacement of said component with reference to the radial distance, from the centre of said disk, of the hole by which scanning is being performed, whereby the magnification of said optical projection system is reduced as the radial distance of said hole decreases.

3. In a television or like transmitter of the type specified a Nipkow disk having scanning apertures suitably disposed to produce an interlaced scan on a continuously moving film, an optical projection system including a compound lens associated with said disk, said compound lens having a component, the effective movement of 20 25 which changes the magnification of said lens without changing substantially the position of the image plane corresponding with a given object plane, and means for varying the refractive index of the media on either side of said 30 35 component with reference to the radial distance, from the centre of said disk, of the hole by which scanning is being performed, whereby the magnification of said optical system is reduced as the radial distance of the said hole decreases.
4. In a television or like transmitter of the type specified including a Nipkow disk having at least two series of scanning holes, said second series of holes being nearer the centre of said disk than said first series of holes, means for correcting 40 45 keystone distortion comprising an optical system including a compound lens for projecting an image of the picture to be transmitted on said disk, said compound lens having a component, the effective movement of which changes the magnification of said lens without changing substantially the position of the image plane corresponding with a given object plane, and means for temporally varying the magnification of said optical projection system with the variation of 50 55 the radial distance from the centre of said disk to an operative scanning hole, said means comprising a pair of glass sheets disposed in planes on opposite sides of the plane of said component, and means to alternately introduce one of said glass sheets on one side of said component when one of said series of holes is scanning and the other of said glass sheets on the other side of said component when the other of said series of holes is scanning.

5. In a television or like transmitter of the type specified a scanning disk, an optical system including a compound lens for projecting an image of a moving film on said disk, said compound lens having a component, the effective movement of which changes the magnification of said lens without changing substantially the position of the image plane corresponding with a given object plane, and means for changing from time to time the thickness of glass in two planes, one on either side of the said component,

the thickness of the glass in one of said planes being increased as the thickness of the glass in the other said plane is decreased.

6. In a television transmitter of the type specified, a scanning disk, means for correcting 5 keystone distortion comprising an optical system, including a compound lens comprising three spaced components, for projecting an image of an object onto said disk, a shaft rotatably mounted in bearings adjacent said compound 10 lens, the axis of said shaft being parallel with the optical axis of said lens, means to rotate said shaft, a pair of disks mounted on said shaft and lying in planes between the central component and each of the outer components of said compound lens, said disks supporting sector shaped glass plates, the projections of said sector-shaped plates upon each other being non-overlapping, whereby as said shaft is rotated said plates are alternately disposed on opposite sides of said 15 20 central component.

7. For a television system of the type specified, a casing, an optical system comprising a compound lens, having three spaced components, of the kind in which the effective displacement of 25 the central component changes the magnification of the lens without substantially changing the position of the image plane corresponding with a given object plane, the outer components of said lens being supported by the walls of said 30 casing and a pedestal mounted within said casing supporting the central component of said lens, a shaft rotatably mounted in bearings in the walls of said casing, the axis of said shaft being parallel with the optical axis of said lens, means to rotate said shaft, two disks perpendicularly mounted on said shaft so as to intercept the optical axis of said lens, and situated one on either side of said central component, each of 35 40 said disks carrying a segment of a circular glass disk, the projections of said glass segments upon each other being non-overlapping.

8. The method of television transmission of moving picture film using interlaced scanning which comprises the steps of projecting said film through an optical system to form an image of said film on a rotating scanning disk having two series of holes, scanning the image with the first series of holes, reducing the width of said image by reducing the magnification of said optical system and thereafter scanning the reduced width image with said second series of holes.

9. The method of television transmission of moving picture films using interlaced scanning which comprises the steps of optically projecting 55 an image of said film onto a rotating scanning disk having two series of holes formed therein, whereof the radial distance between successive holes in the second series is less than the radial distance between successive holes in the first series, scanning the image with the first series of holes, reducing the magnification of the optical projection system and thereby the size of said image and thereafter scanning the reduced image with said second series of holes.

10. In a television transmitter of the type specified a scanning disk having scanning apertures suitably disposed to produce an interlaced scan on a continuously moving film, an optical projection system including a compound lens 70 whose magnification can be varied from time to time for forming an image of a picture to be transmitted on said disk, said scanning disk being formed with two series of scanning holes, whereof the radial distance between successive 75

holes in the second series is less than the radial distance between successive holes in the first series, and means for reducing the size of said image by reducing the magnification of said 5 optical projection system when said image is being scanned by said second series of holes.

11. In a television transmitter of the type specified a scanning disk having scanning apertures suitably disposed to produce an interlaced scan 10 on a continuously moving film an optical projection system including a compound lens whose magnification can be varied from time to time for forming an image of a picture to be transmitted on said disk, said scanning disk being 15 formed with two series of scanning holes, whereof the radial distance between successive holes in the second series is less than the radial distance between successive holes in the first series, and the holes of said second series are of smaller 20 area than the holes of said first series, and means for reducing the size of said image by reducing the magnification of said optical projection system when said image is being scanned by said second series of holes.

12. In a television or like transmitter of the type specified, means for correcting keystone distortion comprising a Nipkow disk having at least two series of scanning holes, said second series of holes being nearer the centre of said disk than 30 said first series of holes, an optical system including a compound lens for projecting an image of the picture to be transmitted on said disk, said compound lens having a component, the effective movement of which changes the magnification 35 of said lens without changing substantially the position of the image plane corresponding with a given object plane, means for varying the magnification of said optical system including a pair of glass sheets disposed in planes on opposite sides 40 of the plane of said component, and means to alternately introduce one of said sheets on one side of said component as one of said series of holes is scanning and the other of said sheets on the other side of said component as the other 45 of said series of holes is scanning whereby the magnification of said projection system is reduced when said image is being scanned by said second series of holes, and means for preventing an alteration in the brightness owing to the 50 change in magnification comprising forming said glass sheet introduced into said optical system when said second series of holes is scanning a glass that has a greater absorption than has the glass of the other glass sheet.

13. In a television transmitter of the type specified, a scanning disk having scanning apertures suitably disposed to produce an interlaced scan on a continuously moving film an optical projection system including a compound lens for 60 forming an image of a moving film on said disk, means for varying the magnification of said optical system with reference to the radial distance from the centre of the said disk of the hole by which scanning is being performed 65 whereby distortion arising substantially from the different speeds of different scanning holes is reduced or abolished and means for reducing the resulting simple keystone distortion comprising a mask fixed relative to the projecting beam and 70 formed with an aperture in the shape of two superimposed trapezia.

14. In a television transmitter of the type specified, a scanning disk having scanning apertures suitably disposed to produce an interlaced scan 75 on a continuously moving film, an optical pro-

jection system including a compound lens for forming an image of a moving film on said disk, means for varying from time to time the magnification of said optical system with reference to the radial distance from the centre of the said disk of the hole by which scanning is being performed whereby distortion arising substantially from the different speeds of different scanning holes is reduced or abolished and means for reducing the resulting simple keystone distortion 10 comprising a gate, over which said film is drawn, formed with two apertures each of the shape of a trapezium separated by a bar of opaque material.

15. A television or like transmitter of the type specified including a scanning disk, an optical projection system associated with said disk and means for producing a periodic variation from time to time in the magnification of said optical system in dependence upon the distance of the 15 operative scanning point of the disk from the centre of said disk, the variation in the magnification of said optical projection system (when effected) being such that the distance of the centre of the single lens equivalent (for paraxial rays) to the said optical system from the scanning disk is reduced as the radial distance of said scanning point decreases.

16. A television or like transmitter of the type specified including a scanning disk, an optical 30 projection system associated with said disk, means for producing a periodic variation from time to time in the magnification of said optical projection system in dependence upon the distance of the operative scanning point of the disk 35 from the centre of said disk, the variation in the magnification of said optical projection system (when effected) being such that the distance of the centre of the single lens equivalent (for paraxial rays) to the said optical system from 40 the scanning disk is reduced as the radial distance of said scanning point from the centre of said disk decreases, the difference between the radii of neighboring scanning points being reduced when the aforesaid distance of the said 45 centre from the scanning disk is reduced.

17. In a television transmitter of the type specified, a scanning disk having scanning apertures suitably disposed to produce an interlaced scan on a continuously moving film, an optical projection system associated with the said disk, means for periodically varying the magnification of said optical system from time to time in dependence upon the distance of the operative scanning point of the disk from the centre of said disk, the variation in the magnification of said optical projection system (when effected) being such that the distance of the centre of a single lens equivalent (for paraxial rays) to the said optical system from the scanning disk is reduced as the radial distance of said scanning point decreases, 60 and means for masking the resulting simple keystone distortion comprising a film gate formed with apertures each of the shape of a trapezium separated by a bar of opaque material.

18. In a television transmitter of the type specified, a scanning disk having scanning apertures suitably disposed to produce an interlaced scan on a continuously moving film, an optical projection system associated with said disk, means for periodically varying the magnification of said optical projection system from time to time in dependence on the distance of the operative scanning point of the disk from the centre of said disk, the variation in the magnification of said 70 disk, the variation in the magnification of said 75

optical projection system (when effected) being such that the distance of the centre of a single lens equivalent (for paraxial rays) to the said optical system from the scanning disk is reduced as the radial distance of said scanning point from the centre of said disk decreases, the difference between the radii of neighbouring scanning points being reduced when the aforesaid distance of the said centre from the scanning disk is produced, and means for masking the resulting simple keystone distortion comprising a film gate formed with apertures each of the shape of a trapezium separated by a bar of opaque material.

19. In a television or like transmitter of the type specified including a scanning disk having scanning apertures suitably disposed to produce an interlaced scan on a continuously moving film, an optical projection system associated with said disk and means for periodically varying the magnification of said optical system from time to time in dependence upon the distance of the operative scanning point of the disk from the centre of said disk, the variation in the magnification of said optical projection system (when effected) being such that the distance of the centre of the single lens equivalent (for paraxial rays) to the said optical system from the scanning disk is reduced as the radial distance of said scanning point decreases, and means for varying the absorption of the optical system when its magnification is varied.

20. In a television transmitter of the type specified, a scanning disk having scanning apertures suitably disposed to produce an interlaced scan on a continuously moving film, an optical projection system associated with said disk, means for periodically varying the magnification of said optical projection system from time to time in dependence upon the distance of the operative scanning point of the disk from the centre of said disk, the variation in the magnification of said optical projection system (when effected) being such that the distance of the centre of the single lens equivalent (for paraxial rays) to the said optical system from the scanning disk is reduced as the radial distance of said scanning point from the centre of said disk decreases, the difference between the radii of neighbouring scanning points being reduced when the aforesaid distance of the said centre from the scanning disk is reduced, means for masking the resulting simple keystone distortion comprising a film gate formed with apertures each of the shape of a trapezium separated by a bar of opaque material, and means for varying the absorption of the optical system when its magnification is varied.

21. A television or like transmitter of the type specified including a Nipkow disk having scanning apertures suitably disposed to produce an interlaced scan on a continuously moving film, an optical projection system associated with said disk and means for periodically varying the magnification of said optical system from time to time in dependence upon the distance of the operative scanning point of the disk from the centre of said disk, the variation of said optical projection system (when effected) being such that the distance of the centre of the single lens equivalent (for paraxial rays) to the said optical system from the scanning disk is reduced as the radial distance of said scanning point decreases, the diameter of holes more remote from the centre of said disk being greater than the

diameter of a plurality of holes nearer to the centre of said disk.

22. A television or like transmitter of the type specified including a Nipkow disk having scanning apertures suitably disposed to produce an interlaced scan on a continuously moving film, an optical projection system associated with said disk, means for periodically varying the magnification of said optical projection system from time to time in dependence upon the distance of the operative scanning point of the disk from the centre of said disk, the variation in the magnification of said optical projection system (when effected) being such that the distance of the centre of the single lens equivalent (for paraxial rays) to the said optical system from the scanning disk is reduced as the radial distance of said scanning point from the centre of said disk decreases, the difference between the radii of neighbouring scanning points being reduced when the aforesaid distance of the said centre from the scanning disk is reduced, the diameter of holes more remote from the centre of said disk being greater than the diameter of a plurality of holes nearer to the centre of said disk.

23. In a television transmitter of the type specified, a Nipkow disk having scanning apertures suitably disposed to produce an interlaced scan on a continuously moving film, an optical projection system associated with the said disk, means for periodically varying the magnification of said optical system from time to time in dependence upon the distance of the operative scanning point of the disk from the centre of said disk, the variation of the magnification of said optical projection system (when effected) being such that the distance of the centre of the single lens equivalent (for paraxial rays) to the said optical system from the scanning disc is reduced as the radial distance of said scanning point decreases, the diameter of holes more remote from the centre of said disk being greater than the diameter of a plurality of holes nearer to the centre of said disk, and means for masking the resulting simple keystone distortion comprising a film gate formed with apertures each of the shape of a trapezium separated by a bar of opaque material.

24. In a television transmitter of the type specified, a Nipkow disk having scanning apertures suitably disposed to produce an interlaced scan on a continuously moving film, an optical projection system associated with said disk, means for periodically varying the magnification of said optical projection system from time to time in dependence upon the distance of the operative scanning point of the disk from the centre of said disk, the variation in the magnification of said optical projection system (when effected) being such that the distance of the centre of a single lens equivalent (for paraxial rays) to the said optical system from the scanning disk is reduced as the radial distance of said scanning point from the centre of said disk decreases, the difference between the radii of neighbouring scanning points being reduced when the aforesaid distance of the said centre from the scanning disk is reduced, the diameter of holes more remote from the centre of said disk being greater than the diameter of a plurality of holes nearer to the centre of said disk, and means for masking the resulting simple keystone distortion comprising a film gate formed with apertures each of the shape of a trapezium separated by a bar of opaque material.

25. In a television transmitter or the like adapted for interlaced scanning of moving film and having a Nipkow disk, means for changing compound keystone distortion to simple keystone distortion, said means comprising an optical system for projecting said film on said disk and

means for varying the magnification of said optical system, and means for correcting the resulting simple keystone distortion.
